Primary Examiner — Darlington Ly(74) *Attorney, Agent, or Firm* — Inventa Capital PLC(57) **CLAIM**

I claim the ornamental design for an all-terrain vehicle, as shown and described.

DESCRIPTION

FIG. 1 is a front and left side perspective view of the all-terrain vehicle showing my new design;
 FIG. 2 is a front perspective view thereof;
 FIG. 3 is a rear perspective view thereof;
 FIG. 4 is a left side elevation view thereof;
 FIG. 5 is a right side elevation view thereof;
 FIG. 6 is a top and front perspective view thereof; and,
 FIG. 7 is a rear and left side perspective view thereof.
 The broken lines in the drawings illustrate portions of the all-terrain vehicle that form no part of the claimed design.
